UNITED STATES PATENT OFFICE.

MADISON F. BATES, OF LANSING, MICHIGAN.

CARBURETER.

1,160,239.

Specification of Letters Patent. Patented Nov. 16, 1915.

Application filed May 5, 1913. Serial No. 765,421.

To all whom it may concern:

Be it known that I, MADISON F. BATES, a citizen of the United States, residing at Lansing, county of Ingham, State of Michigan, have invented a certain new and useful Improvement in Carbureters; and declare the following to be a full, clear, and exact description of the same, such as will enable others skilled in the art to which it pertains 10 to make and use the same, reference being had to the accompanying drawings, which form a part of this specification.

My invention relates to carbureters and consists in the improvements hereinafter described and pointed out in the claims.

In the accompanying drawings: Figure 1, is a side elevation of a carbureter embodying my invention. Fig. 2, is a horizontal section on the line B—B Figs. 1 and 4. Fig. 20 3, is a section on the line D—D Figs. 1, 2 and 4. Fig. 4, is a section on the line E—E Fig. 2.

a *a* represents the casing as a whole.

b is the passage leading to the engine.

25 *c* *c* are the intake passages.

d is an intake passage for the auxiliary air supply.

30 *e* and *g* are disks integral with or secured upon the valve stem *f* which latter may reciprocate in the casing *a*.

2, is a port, the opening through which may be regulated by the disk *g*, and 3 is a second port, the opening through which may be regulated by the disk *e*. These ports are 35 at a distance apart equal to that of the disks *e* and *g* so that the opening through the one is equal to the opening through the other.

h is a spring tending to press the stem *f* and disks *g* and *e* to the position at which 40 they leave the ports 2 and 3 open.

s is a lever arm, by which the stem *f* and disks *e* and *g* may be manipulated to regulate the opening through the ports 2 and 3.

45 *i* is a check valve adapted to open inward and when upon its seat to close the port forming a communication between the passage *d* and the outside air.

j, is a stem rising from the valve *i*, and *k* is a spring acting to yieldingly press the 50 valve *i* toward its seat.

m is the intake passage through which the liquid fuel is supplied to a reservoir *n*. There is a float valve mechanism in the reservoir *n* by which the level of the liquid fuel 55 in said reservoir may be controlled.

o is a conduit leading from the reservoir *n*

below the level of the liquid therein and extending in two branches which terminate in the nozzles *q* and *r* each of which opens into a branch of the intake passage *c*.

One branch of the intake passage *c* communicates with the outlet passage *b* through the port 2 and the other through the port 3.

t is an intake passage for water, the opening through which is controlled by an inwardly opening check valve *u*.

The maximum flow of liquid through the passage *o* is controlled by the needle valve *p* and through the conduit *x* by a needle valve *v*. The conduit *x* opens into the passage *d* 70 through the opening *w*.

The operation of the above described device is as follows: The passage *b* is connected with the engine and the charge is drawn therethrough from the carbureter, the main air supplied passing in through the passages *c* taking up the combustible vapor from the nozzles *q* and *r* and distributing and thoroughly mixing the vapor and air as it passes through the narrow and extended 75 openings past the disks *e* and *g*. Hydrocarbon is supplied through the passage *m* and is delivered, as described, through the nozzles *q* and *r*. Water is supplied through the passage *t* and conduit *x*. When the draft of the engine has increased to a sufficient extent the valve *u* is raised permitting water to pass through the conduit *x* and the valve *i* is drawn from its seat permitting the entrance of an auxiliary supply of air 80 which takes up the water in the form of vapor and carries it through the ports 2 and 3 and thoroughly mixes it with the rest of the charge.

What I claim is:

1. A carbureter having two intake passages and an outlet passage, a port between each of said intake passages and said outlet passage, a disk valve adapted to regulate the opening through each of said ports by a movement perpendicular to the plane of said ports, said disks being joined together and adapted to open or close said ports by a simultaneous movement in the same direction, means for supplying a liquid to be vaporized and mixed with the air to each of said intake passages.

2. A carbureter having two intake passages and an outlet passage, a port between each of said intake passages and said outlet 100 passage, a disk valve adapted to regulate the opening through each of said ports by a
